PORTABLE LAMP

Filed June 27, 1935

FIG. 1.

FIG. 2.

Inventor:
Arthur B. Oday,
by Harry E. Dunham
His Attorney.

UNITED STATES PATENT OFFICE

2,146,591

PORTABLE LAMP

Arthur B. Oday, Cleveland, Ohio, assignor to
General Electric Company, a corporation of
New York

Application June 27, 1935, Serial No. 28,619

2 Claims. (Cl. 240—81)

My invention relates to so-called bridge lamps. One of the features of my lamp is that it comprises the combination of an incandescent lamp support arranged so that the lamp is supported base upward and is provided also with a suitable shield and light transmitting and diffusing screen so as to prevent glare especially when the lamp is tilted. Another feature is the combination of the aforesaid parts with a suitable shade or reflector. Other features and advantages of my invention appear from the description which follows of species thereof and from the accompanying drawing.

In the drawing, Fig. 1 is a side elevation partially broken away of the lighting unit of my invention; Fig. 2 is a plan view of one half of said unit; and Fig. 3 is a side elevation partially broken away of a portion of a modification of the lighting unit of my invention.

20 The lighting unit of my invention shown in Figs. 1 and 2 comprises a shade 10 of frusto-conical form which is preferably made of a translucent material such as parchment or heavy paper and which is coated on the inside with a white 25 paint of high reflecting factor. The shade 10 is stiffened with wires 11 and 12 located in the upper and lower edges respectively and is supported through three radially extending wires 13 which are attached to wire 11 and a collar 14. 30 The collar 14 is preferably provided with threads by which it is screwed into the shell of the electric lamp socket 15 and supports in conjunction with the wires 13 the translucent screen 16 which is preferably of opal glass. The translucent 35 screen 16 is provided with an aperture for the socket 15 and covers over the entire open space between the shade 10 and the socket 15. The screen 16 is held in place by the broken ring 17 which springs outward into the indentations in 40 wires 13 and prevents direct illumination from the light source 18 mounted in the socket 15 from passing upward from the lighting unit. The translucent material of the screen 16 causes some 45 of the light to be reflected downward so that it will pass out the bottom opening in the shade 10.

A shield 19 is mounted below the light source 18 in a position to intercept all illumination which would otherwise pass directly out the bottom opening in the shade 10 from the light source 18. 50 The shield 19 is supported by a pair of wires 20 extending downward from wires 13 which pass through apertures in the shield and are bent back forming a loop, and by wire 21 which extends downward from one of the wires 13 and engages 55 the edge of the shield. Wire 21 has an indented

portion in which the edge of the shield 19 rests and may be sprung back so that the shield can be tilted and a new light source inserted in the socket 15. The shield 19 preferably has a very good reflecting surface on the inside and has 5 either an oxidized aluminum or painted surface on the outside so that it will pick up light from the shade and be less conspicuous.

The outside of the shade should be treated so that the differences in brightness of the various 10 portions of the unit are not objectionable. In this instance, the dark area 22 of the shade 10 resulting from the position of the shield 16 is separated from the remainder of the shade by opaque bands 23 and 24. The lighting unit is 15 shown in the drawing attached to a bridge lamp type standard 25 through arm 25' through which its advantages may best be realized since the lamp is usually tilted.

The modified lighting unit of my invention 20 shown in Fig. 3 differs from the preceding unit principally in its method of mounting. In this instance, the collar 14 is screwed on the socket extension 26 which is provided with one portion 25' for screwing into a lamp socket and which provides a socket into which the light source 18 can be screwed. The top of the shade 10 is extended upward farther so that it will take the same position with reference to the lighting standard as the shade of the lighting unit previously described. Bands 27 and 28 are placed on the shade 30 10 to separate the comparatively light and dark areas.

What I claim as new and desire to secure by Letters Patent of the United States is:

1. In a lamp of the character described, the combination of a standard and an arm extending therefrom, a socket supported by said arm and adapted to support an electric lamp, base upward, a shade supported by said socket, a shield disposed below said electric lamp, a plurality of wire supports connecting said shield and shade, and a light transmitting and diffusing screen supported between said shade and said socket, at least one of said supports having a loop at its end 45 extending through a hole at the rim of said shield and at least one other of said supports detachably engaging the rim of said shield to permit said shield to be swung downward for insertion of said lamp.

2. In a lamp of the character described, the combination of a standard and an arm extending therefrom, a socket supported by said arm and adapted to support an electric lamp, base upward, a collar mounted on said socket, a frusto- 50 55

5 conical shade surrounding said electric lamp to reflect the light therefrom downwardly, a plurality of wires extending radially outward from said collar and engaging the upper end of said shade to support it, a flat light-transmitting and diffusing screen covering the opening at the upper end of said shade and having a central opening through which said socket extends, said screen being supported by said radially extending wires,

a shield disposed below said electric lamp to prevent the downward projection of direct light from said lamp, and a plurality of wires extending downward from said radially extending wires and engaging said shield to support it, at least one of said downwardly extending wires being detachable to allow tilting of said shield for insertion of said electric lamp. 5

ARTHUR B. ODAY.
